Primary Examiner — Jennifer Rivard(74) *Attorney, Agent, or Firm* — Foley & Lardner LLP(57) **CLAIM**

I claim the ornamental design for a cosmetic abrasion device, as shown and described.

DESCRIPTION

FIG. 1 is a top, front perspective view of an embodiment of the claimed design;

FIG. 2 is a top, rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The ornamental design which is claimed is shown in solid lines in the drawings. The equal length broken lines illustrate portions of the design. The dash-dot broken lines illustrate the boundaries of the design. None of the broken lines forms part of the claimed design.
